UNITED STATES PATENT OFFICE.

EBERHARD SCHNEIDER, OF NEW YORK, N. Y.

MOVING-PICTURE-PROJECTING APPARATUS.

1,274,607.

Specification of Letters Patent. Patented Aug. 6, 1918.

Application filed February 19, 1914. Serial No. 819,607.

To all whom it may concern:

Be it known that I, EBERHARD SCHNEIDER, a citizen of the United States and a resident of the borough of Manhattan, in the county of New York and State of New York, have invented certain new and useful Improvements in Moving-Picture-Projecting Apparatus, of which the following is a specification.

10 This invention relates to a moving picture projecting apparatus, and its novelty is directed particularly to its collapsible features.

With this apparatus, a frame has formed therewith a pair of film magazines with their axes coincident. The elements of a picture projecting apparatus are mounted on a frame plate, which latter is pivoted to the frame of the machine and which can be 20 located in a vertical position when in use and can be swung to a horizontal position adjacent to the frame when not being used. A lamp is pivoted to the frame which, when in use, is normally in a horizontal position, and 25 which can be swung at right angles to this position and located adjacent to the frame of the machine.

The invention specifically comprises among its improvements a lamp connected to a condenser shell having a resistance coil wound around the body thereof, to allow the lenses in said shell to cool gradually when the source of light is extinguished and to prevent said lenses from cracking.

35 The propelling mechanism of the invention has incorporated therewith sprocket drums with sprocket chain wheels, operated by a chain comprising balls that are flexibly connected, and by virtue of the chains, the 40 sprocket wheels with their drums can be journaled with their axes inclined to each other. This disposition of the drums allows the film magazines of the invention to be placed side by side.

45 Provision is made to view the film as it is wound up on one of the film reels of the apparatus.

Figure 1 represents a side elevation of the 50 projecting apparatus, Fig. 2 shows a top plan view of Fig. 1, Fig. 3 is a left hand side view of Fig. 1, Fig. 4 represents a partial right-hand side view and section of Fig. 1 on the line 4, 4, Fig. 5 shows a right hand side view of Fig. 1, Fig. 6 is an elevation of 55 a detail, Fig. 7 shows a left hand side view

of Fig. 6, Fig. 7^a is a section of Fig. 7 on the line 7^a, 7^a, Fig. 8 represents an elevation of a detail, Fig. 9 is a top plan view of Fig. 8 with an element in section as on the line 9, 9, of Fig. 4, Fig. 10 represents a partial section of Fig. 8 as on the line 10, 10, with a few elements added thereto in section as on line 9, 9, of Fig. 4, Fig. 11 represents an elevation of a detail, Fig. 12 shows a left hand side view of Fig. 11, Fig. 13 is a top plan view of Fig. 11, Fig. 14 represents a plan view of a detail, Fig. 15 shows an enlarged top plan view of the lamp of the apparatus, Fig. 16 represents a section of Fig. 15 on the line 16, 16, Fig. 16^a shows a top plan view of some of the details of Fig. 16, Fig. 17 is a right hand view of Fig. 15, Fig. 18 shows a partial section of Fig. 16 on the line 18, 18, Fig. 19 represents a fragmentary inside view of a lamp head, Fig. 20 shows 70 an elevation of a detail, Fig. 21 represents a right hand side view of Fig. 20, Fig. 22 shows a top plan view of a detail of the lamp, Fig. 23 represents a bottom view of Fig. 22, Fig. 24 represents an end view of Fig. 22, Fig. 25 shows a fragmentary enlarged sectional view of a sprocket chain, Fig. 26 shows an enlarged fragmentary portion of a sprocket wheel and Fig. 27 represents a left hand side view of Fig. 26. 75

The invention is represented to comprise a frame 20 that has formed therewith a pair of film magazines 21, 22, that have respectively hinged thereto the doors 23 and 24. The door 23 has an opening over which is secured a frame 25 with a piece of transparent material 26 like mica, so that an observer can view the interior of the magazine 23. The frame 20 has extending therefrom the front legs 30 and the rear legs 31. A pivot 34 with the horizontal abutting face 35 extends from the rear portion of the frame 20. A pivot 36 threaded at 37 extends from the pivot bracket 34. A lug 38 with a bolt 39 carrying the wing nut 40 extends 90 from the frame 20. An adjusting sleeve 43 with the bifurcated end 44 is pivoted on the pivot 36. A spring 45 encircles the pivot 37 between the said bifurcated end 44 and the pivot bracket 34. A knurled nut 46 on the threaded end 37 of the pivot 36 bears against the bifurcated end 34. The coaction of the nut 46 and spring 45 provides flexible adjusting means for the lateral adjustment of the sleeve 43. A lug 48 with a pin 49 100

105

110

extends from the lower face of the sleeve 43, and a link 50 with the elongated slot 51 connects the pin 49 and the bolt 39. The slot 51 permits the link 50 when the wing nut 40 is unscrewed to lower, when the adjusting sleeve 43 is swung down on the pivot 36. An adjustable supporting bar 52 is supported in the sleeve 43.

A condenser shell is shown at 58 that has 10 extending from its lower end the sleeve 59 that is adjustably supported on the supporting bar 52, and that can be longitudinally adjusted on said bar. The shell 58 has extending from its outer cylindrical surface 15 the flange 60. A cylindrical projection 62 with openings 63 on the sides thereof extends from the shell 58. Screws 64 in said projection can clamp a slide carrier 65 in position. A tapered barrel 66 extends from 20 the cylindrical projection 62. Lenses 70, 71 are located in the shell 58 and are held in position by the tension of the spring 72. A lamp is shown with the inner sleeve 73 that has formed therewith the flange 74. Bayonet joints with the screw pins 75 are formed between the inner sleeve 73 and the shell 58. An outer adjustable sleeve 78 having the ventilating openings 79 and the longitudinal slots 80 is supported upon the inner sleeve 73, and adjusting pins 81 extending from the sleeve 73, pass through the slots 80, so that by means of said pins the outer sleeve 78 can be adjusted to different 30 positions relatively to the sleeve 73. An opening 83 is formed in the lower face of the outer sleeve 78. A lamp head with the barrel 88 is locked to the sleeve 78, by means of bayonet joints having the screw pins 89. A spring clamp 89^a has one end fastened 40 to the barrel 88 and the other end has extending therefrom a latch pin 89^b which passes through an opening in the barrel 88 and an opening 89^c in the sleeve 78. A ventilating lip 90 with the openings 91 extends 45 from the barrel 88, the openings 91 being located on the opposite sides of the openings 79 in the plan view. An annular air duct 91^a is formed between the inner face of the lip 90 and the sleeve 78. A barrel 50 92, having in threaded engagement therewith the clamp screw 93 extends from the barrel 88, and its bore registers with the opening 83 in the sleeve 78. A source of light independent of the carbons to be described, can be secured in the barrel 92 by 55 means of the screw 93. A hood 94 extends from the barrel 88 and has formed therewith a pair of sleeves designated by the numerals 95, 96. In each of the sleeves 95, 96 is located at its lower inner portion a washer 97 of insulating material, and upon which bears a barrel 98 of insulating material. A washer 99 of insulating material caps the barrel 98 and metallic washers 100 60 bear upon each of the washers 99, and fit the

inner cylindrical surfaces of the sleeves 95 and 96. A projection 101 extends from each of the sleeves 95 and 96 and contains a sleeve of insulating material 102, that meets the barrel 98.

A binding post 108, with the threaded shank 109 and clamping screw 110 is located within the sleeve 102 of insulating material. A spring clamp with the jaws 112, 113, 114, is located in the barrel 98 and has 70 extending therefrom the threaded lug 115 which is engaged by the threaded shank 109 of the binding post 108. A pair of carbons 118 are tightly clamped in proper position by the said spring clamps. An observation opening with a colored glass 119 is formed in the hood 94.

Around the outer surface of the shell 58 is located a sleeve 120 of insulating material, like mica. A coil of wire 121 is wound 85 around the sleeve 120. A sleeve 122 of insulating material, like mica, covers the said coil of wire. A protecting cover 123 extends from the flange 60 and forms an air duct 124. Binding posts 128, 129 and 130 90 extend from the cover 123. The binding post 128 connects with one end of the coil 121 and the binding post 130 connects with the other end thereof, while the binding post 129 connects with the coil so as to include about two-thirds thereof between it and the binding post 128 to constitute a cut out if required.

A pair of main line wires for electric current are indicated at 135, 136. A branch 100 wire 137 extends from the wire 135 and connects with the binding post of the sleeve 95. A wire 138 has one end connected to the binding post of the sleeve 96 and its other end is connected to the binding post 128. A 105 branch wire 140 in this instance, extends from the wire 136 and connects with the binding post 130, although if required the wire 140 may be connected to the binding post 129 and thereby is provided a cut out 110 to control the electric current for the carbons 118.

From the frame 20 extends a hinge bracket 145 which carries a hinge bolt 146 with the wing nut 147. A frame plate 150 115 of a moving picture projecting apparatus has formed therewith the foot 151. Journal bearings 152, 153 are formed with said foot and are hinged on the bolt 146 to enable the frame plate 150 to be swung in the direction of the arrow D from the position indicated in the drawing to a horizontal position with its swinging end bearing on the abutting face 35. The frame plate 150 has formed therewith the opening 155 for the 120 field of the lens to be described. Vertical flanges 156 on the opposite sides of said opening 155 are formed with said frame plate. An elongated opening 163 is formed 125 in the plate 150 for the spindle 164 that car- 130

- ries at one end the shutter 165 having the openings 167, 168. A sprocket pinion 170 is fastened to the other end of the spindle 164. A pivot 172 is supported in the frame plate 150. A bifurcated lug 175 extends from the arm 173 which straddles a sleeve 176 supported on the spindle 164. The arm 174 has one end supported on the pivot 172 and the other end is connected to the spindle 164. A washer 177 is supported on the said spindle 164 between the arm 174 and the sprocket pinion 170. An arm 180 that can be swung in different positions is pivoted on the pivot 172. It has journalized to its swinging end the guide roller 181, and has a lug 182 that can engage the arm 174. The guide roller 181 guides the chain to be described having the balls 278, so that the latter engages the sprocket pinion 170 and to perform this function properly the guide roller 181 must be adjacent to said sprocket pinion 170. When the lug 182 bears upon the arm 174 the roller 181 is in proper position with respect to the pinion 170. When the arm 173 is raised it carries the arm 180 therewith by virtue of the lug 182 engaging the arm 174. Threaded ends 183 of the pivot 172 carry nuts and the spring washers 184. By means of the adjusting arm 173 the sprocket pinion 170 and guide roller 181 and film gripping or framing device to be described can be located in different positions.
- A pair of lugs 190 extend from the frame plate 150 and support the pin 191 of the adjustable film clamp 192 having elongated openings 193. The clamp 192 is located between the vertical flanges 156. The pin 191 has fastened thereto and supports the helical spring 194 having the legs 195 and 196. The film clamp 192 has formed in the body thereof the elongated openings 197, 198 and has extending therefrom the posts 199, 200 and the handle 201. The end of the legs 195, 196 engage openings 197 formed in the post 199, and by means of the tension of the spring 194 and its legs, the film clamp is made to bear with the requisite tension against the film 202 used in the apparatus. The body of the film clamp has formed therein an opening 203 that registers with the opening 155, of the frame plate 150. Pairs of lugs 206, 207, extend up from the film clamp 192. The lugs 206 have pivoted therein the hinge pin 208 and the lugs 207 have hinged therein the hinge pin 209. The pin 208 has fastened thereto the fire door 215, and the hinge pin 209 has fastened thereto the fire door 216. The hinge pin 208 has extending therefrom the arm 217 and the pin 209 has extending therefrom the arm 218, and a link 219 connects said arms 217 and 218. The pin 208 has also extending therefrom the arm 220. The guide roller 181 carries a counterweight 224, and the arm 225 which engages the arm 220, and when the said
- roller turns in the direction of the arrow A it pulls down the arm 220, and thereby both the fire doors 215 and 216 are opened and maintained open, during a tendency of said roller 181 to turn in said direction. 70 The doors close by gravity when said action of the roller 181 ceases, and the said roller is at the same time turned on its axis by the counterweight 224 and disengages the arm 225 from the arm 220. A protecting shield 75 226 with an opening 227 is supported on the posts 199 and 200.
- From the frame plate 150 extends a bracket 230 that carries a pin 231 which has a threaded end 232 with a wing nut 233. 80 A lower sprocket drum 235 with the pulley 236 and sprocket wheel 237 is journalized on the pin 231. A driving pin 238 is carried by said sprocket drum 235. A lug 239 extends from the frame 20 which has one end of a link 240 having an elongated slot 241 pinned thereto, while the other end of the link is supported on the pin 231, the latter passing through the slot 241. By unscrewing the wing nut 233 the frame plate 150 may be 85 swung in the direction of the arrow D to a horizontal position. The magazines 21 and 22 are divided by the dividing wall 248, which supports the reel pivot 249, that extends into both magazines. A discharging 90 reel 250 is journalized on the pivot 249 in the magazine 22 and a receiving reel 251 is journalized on the pivot 249 of the magazine 21. A pulley 252 detachably connected to the reel 251 is journalized on the pin 249. A 100 spring belt 253 connects the pulley 252 with the pulley 236, passing through openings in the roof of the magazine 21. The flexibility of the belt 253 allows the frame plate 150 to be located either in a vertical or horizontal 105 position.
- From the frame plate 150 extends preferably at an angle of 45 degrees the journal bracket 255, to which is journalized the upper sprocket drum 256, and sprocket wheel 110 257. The wheel 257 has formed on its periphery the curved bearing surfaces 258, and notches 259 are formed in the ridges between said surfaces. The said notches engage the wires of the chain to be described. 115 A bracket 262 extends from the frame plate 150 which has extending therefrom a pivot 263 on which is journalized a guide roller 264. An arm 265 extends from the roller 264 and carries a pivot 266, on which latter is 120 journalized a clamping roller 267.
- From the frame plate 150 extends a clamping arm 270 on which is journalized a pair of clamping rollers 271, 272, for the sprocket drum 285. A spring 273 holds the 125 arm 270 in proper operative position. A bracket 275 extends from the frame plate 150 and adjustably supports a pivot 276 on which is journalized a guide pulley 277. A sprocket chain comprises the balls 278, 130

flexibly connected by the wires 279 having the upset ends 280, extends under the sprocket wheel 237, passes up under the guide pulley 277 and from thence over the 5 sprocket wheel 257, and then between the guide roller 181 and sprocket pinion 170. The chain then engages both the guide pulley 181 and the sprocket pinion 170 on its way back to the sprocket wheel 237. A 10 guide sector 280 extends from the frame plate 150 for the adjusting arm 173. A bracket 281 with the pins 282, 283 extends from the frame plate 150. A lens casing for the lens of the apparatus is indicated at 288 15 with the flange 289, which latter has an opening 290 and a slot 291. The opening 290 is engaged by the pin 282 and the slot 291 is engaged by the pin 283, by means of which the lens casing can be swung clear of 20 the opening 155 of the frame plate 150.

A guide bar 294 and guide brackets 296, 297 extend from the frame plate 150. A sliding guide rod 298 is guided in the brackets 296, 297. A crosshead 299 is fastened to the rod 298, and is guided on the bar 294. A pin 300 with its axis to the left of the vertical plane passing through the spindle 164 extends from the crosshead 299 and a pin 301 extends from the shutter 165. 30 A connecting rod 302 connects the pins 300 and 301. A gripping pin support 305 is fastened to the crosshead 299 by means of the screw 306. It has formed therewith eyes 307 which support a hinge pin 308.

35 Gripping pins 309 are hinged to the hinge pin 308. The pins 309 extend through openings 310 in the support 305 through the openings 197, 198 in the film clamp 192, and through the openings 311 in the frame plate 40 150 to engage the perforation in the film 202. Each of the gripping pins 309 has formed therewith the leg 315 that bears on the support 305. A lug 316 extends from the support 305 and has extending therefrom a 45 spring with the arms 317 that bear on the legs 315.

A lug 320 extends from the frame plate 150 in which is clamped a pin 321 that in 50 turn has pinned thereto the frame 322 of a lens 323. The latter is used in place of the lens in the casing 288 in case the apparatus is used as a stereopticon, and which can be done by swinging the frame plate 150 to a horizontal position with the lens casing 288 55 swung from the opening 155.

In Figs. 20 and 21 is represented the driving crank, comprising the hollow barrel 330 which has extending from one end thereof the flange 331 with the hook 332. An arm 333 60 with the handle 334 extends from the other end of the barrel 330. To operate the machine the barrel 330 encircles the pin 231 and the hook 332 locks with the pin 238 of the sprocket drum 235. In the crowns of the 65 magazines 21 and 22 are formed openings

340, 341, and guide rollers 342 and 343 are journaled to the frame 20 adjacent to said openings.

The film 202 extends from the reel 250 through the opening 340 over the roller 342, 70 It then passes over the guide roller 264, sprocket drum 256, thence under the film clamp 192, in the path of the opening 155, in the frame plate 150. The film then is engaged by the sprocket drum 235, leads over 75 the roller 341 into the magazine 21 to be wound up by the reel 251.

The adjustments and operations of the elements of the apparatus have been described. A particular novelty of the invention consists in the collapsible feature of its elements, by means of which the frame plate 150, with its element for propelling the film 202 can be swung from the vertical position shown in the drawings to a horizontal position, so that the swinging end of said frame plate bears on the horizontal abutting face 35 of the bracket 34 and locates said frame plate 150 adjacent to the frame 20. A second novel feature of the invention consists 90 in the means described to swing the lamp with its appurtenances on the pivot 36 to assume a vertical position adjacent to the frame 20. These novel collapsible features enable the apparatus to be packed in a case 95 of small dimensions.

The coil of wire 120 constitutes a resistance coil or rheostat for the current that energizes the carbons 118. It obviates the necessity of an independent rheostat and its 100 heat after the electric current is shut off, enables the lenses 70 and 71 to cool gradually and prevents them from cracking.

The adjusting arm 173 and the appurtenances controlled thereby, allows the spindle 105 164 with the shutter 165, and the gripping pin support 305 with its gripping pins 309, to be vertically adjusted, to locate the film 202 in proper register with the opening 155 in the frame plate, and thereby an efficient 110 framing device is produced.

The chain with the balls or spheres 278 permits the easy and efficient connection of the sprocket wheels 237, 251 and 170, that turn in planes making angles with each 115 other.

The inclination of forty-five degrees of the axis of the upper sprocket drum 256 with the frame plate 150, adjusts the film 202 so that it can easily leave the magazine 22 and wind around said drum and then easily be located under the film clamp 192.

Various modifications may be made in the construction shown without departing from the spirit of the invention. The resistance coil 121 might be located on the inside of the condenser shell 58, or it might be located on the outside or inside of the sleeve 78 or other portion of the lamp.

Having described my invention, what I 130

desire to secure by Letters Patent and claim is:

1. In an apparatus of the character described the combination of a frame, a pair of film magazines in the frame, film propelling and projecting means pivoted to the frame, a lamp pivoted to the frame, and means to locate said lamp with its longitudinal axis in a horizontal plane and also in a vertical plane.
2. In an apparatus of the character described the combination of a frame, a frame plate pivoted to the frame, means on the frame plate for propelling a film, means connected with said plate for projecting pictures of said film, a lamp pivoted to said frame, and means with a flexible element to laterally adjust said lamp.
3. In an apparatus of the character described the combination of a frame, a pair of film magazines in the frame, a frame plate pivoted to the frame, means to locate the frame plate in different positions, propelling and projecting means for said film connected to the frame plate, a lamp pivoted to the frame, collapsible members comprising said lamp and means to locate said lamp with its longitudinal axis in a horizontal direction and also in a vertical direction.
4. In an apparatus of the character described the combination of a frame, a pair of film magazines in the frame, a frame plate pivoted to the frame, film propelling and projecting means connected to said frame plate, means to clamp said frame plate in a vertical position and to enable it to take a horizontal position adjacent to said frame, a lamp pivoted to the frame, means to clamp said lamp with its longitudinal axis in a horizontal direction and to locate it in a vertical direction adjacent to said frame.
5. In an apparatus of the character described the combination of a frame, a pair of film magazines in the frame, a frame plate pivoted to the frame, film propelling and projecting means connected to said frame plate, means to clamp said frame plate in a vertical position and to enable it to take a horizontal position adjacent to said frame, a lamp pivoted to the frame, means to clamp said lamp with its longitudinal axis in a horizontal direction and to locate it in a vertical direction adjacent to said frame, and means to laterally adjust said lamp to locate it in proper position for the said projecting means.
6. In an apparatus of the character described the combination of a frame, a pair of film magazines in the frame, a hinge bracket extending from the frame, a frame plate pivoted to said hinge bracket, film propelling and projecting means connected to said frame plate, a bracket extending from the frame plate, a pin extending from the latter bracket, a link with one end pinned to said frame and the other end connected to said pin, and means to clamp the link to the latter bracket, the said link with its adjacent appurtenances enabling the frame plate to be clamped in different positions, the said frame having an abutting face to maintain the frame plate in a horizontal position.
7. In an apparatus of the character described the combination of a frame, a frame plate pivoted to the frame, means to locate the frame plate in a horizontal or vertical position, film propelling and projecting means connected to the frame plate, a lens adjustably connected to the frame plate performing its function when the frame plate is in its horizontal position, a condenser shell pivoted to the frame performing its function when the frame plate is in a vertical position, lenses for said shell, a slide carrier supported in said shell and a lamp connected to said shell.
8. In an apparatus of the character described the combination of a frame, a frame plate pivoted to the frame, film propelling means connected to the frame plate, a bracket extending from the frame plate, a pair of pins extending from said bracket, a lens casing with a flange having an opening and a slot, said opening engaging one of said pins and said slot locking with the other pin when said lens is in operative position and a lamp pivotally connected to said frame.
9. In an apparatus of the character described the combination of a frame, a film magazine in the frame, a frame plate pivoted to the frame, means to maintain the frame plate in a horizontal or vertical position, film propelling means connected to the frame plate, a lens with film projecting means connected to the frame plate performing its function when the frame plate is in a vertical position, and a second lens connected to the frame plate to be enabled to use the apparatus as a stereopticon when the frame plate is in a horizontal position.

Signed at the borough of Manhattan, in the county of New York and State of New York, this eleventh day of February, A. D. 1914.
